UNITED STATES PATENT OFFICE.

DE KELLER STAMEY, OF NEW YORK, N. Y.

PENCIL-SHARPENER.

No. 853,836.

Specification of Letters Patent.

Patented May 14, 1907.

Application filed December 5, 1906. Serial No. 346,491.

To all whom it may concern:

Be it known that I, DE KELLER STAMEY, a citizen of the United States of America, residing at New York, in the county of New York and State of New York, have invented new and useful Improvements in Pencil-Sharpeners, of which the following is a specification.

This invention relates to pencil sharpeners, and one of the principal objects of the same is to provide a simple and efficient device for sharpening pencils and for pointing the leads thereof.

Another object of the invention is to provide a pencil sharpener in which the spiral cutting edge is presented to the pencil simultaneously at all points from the lower to the upper end of the tapering point of the pencil.

These and other objects are attained by means of the construction illustrated in the accompanying drawings, in which:

Figure 1 is a side elevation of a pencil sharpener made in accordance with my invention. Fig. 2 is a central vertical section of the same. Fig. 3 is a plan view of the same.

Fig. 4 is a vertical section of a modified form of my invention. Fig. 5 is a sectional view of a cap or cover for the sharpener.

Referring to the drawing for a more particular description of my invention, the numeral 1 designates a frusto-conical or tapering metallic tube having a spiral slot 2 therein which extends from a point about midway thereof and terminating at the lower end, as at 3. The upper edge of the slot 2 is sharpened and bent slightly inward to form a cutting edge 4. The upper end of the tube 1 is cylindrical or of equal diameter, and is provided with a depression 5 which has a roughened wall and is designed for the purpose of pointing the lead of the pencil after the same has been sharpened. A sleeve or ring 6 surrounds the cylindrical portion 7, said ring being provided with a recess 8 which engages the depression 5 and thus firmly seats the ring 6 upon said cylindrical portion 7 and prevents said ring from turning independently of the sharpener. As shown in Fig. 4, the cutting blade 4^a is formed separately from the tubular portion 1^a, said blade being secured at the upper edge of the slot 2^a, and the cutting edge *a* projecting in-

ward through the slot 2^a at an angle, as shown in the drawing.

From the foregoing it will be obvious that a pencil inserted in the sharpener and the pencil being rotated by grasping the ring 6 and turning the pencil in the sharpener, the edge 4 or *a* will have contact on the point of the pencil from one end of the blade to the other, and owing to the angle at which the cutting edge is disposed relatively to the tube, the wood of the pencil will be cut on a spiral line across the grain of the wood, as will be obvious. After the pencil has been sharpened, the lead may be pointed by rotating the same within the depression 5 of the sharpener.

The spiral cutting edge may be arranged to extend reversely to that shown in the drawing, and the pencil sharpener may be rotated instead of the pencil without departing from the spirit of my invention. A cap or cover *c* shown in Fig. 5, and in dotted lines in Fig. 1, may be utilized for covering the sharpener.

Having thus described the invention, what I claim is:

1. A pencil sharpener comprising a tapering tube having a spiral slot therein and a cutting edge projecting at an angle in said slot, and a depression in one end of said tube for pointing the lead, substantially as described.

2. A pencil sharpener having a cutting edge, a cylindrical portion at one end thereof, a depression formed in said cylindrical portion, said depression being roughened for pointing the pencil lead.

3. A pencil sharpener comprising a tapering tube having a cylindrical portion at one end, a depression formed in said cylindrical portion, and a ring provided with a recess to engage said depression to prevent the ring from turning upon said cylindrical portion, said depression being roughened for pointing the pencil lead, substantially as described.

In testimony whereof, I affix my signature in presence of two witnesses.

DE KELLER STAMEY.

Witnesses:

ALPHONSE WEINER,

ALFRED WEINER JR.
